GORDON R. ROWAN, OF OAK RIDGE, MICHIGAN, ASSIGNOR OF ONE-HALF TO ROBERTS P. HUDSON AND ALBERT B. DAVIDSON, BOTH OF SAULT STE. MARIE, MICHIGAN.

DREDGING-BUCKET.

1,186,684.

Specification of Letters Patent. Patented June 13, 1916.

Application filed September 9, 1914. Serial No. 860,860.

To all whom it may concern:

Be it known that I, GORDON R. ROWAN, a subject of the King of Great Britain, residing at Oak Ridge, in the county of Chippewa and State of Michigan, have invented a new and useful Dredging-Bucket, of which the following is a specification.

The invention relates to improvements in dredging and dredging buckets of the 10 orange peel and clam shell type.

The object of the present invention is to improve the construction of clam shell and orange peel dredging buckets and to provide a simple, practical, and efficient bucket 15 of this character, of comparatively inexpensive construction, which will be positive and reliable in operation and adapted to simplify the operation of dredging buckets of this type.

20 A further object of the invention is to provide a dredging bucket of this character equipped with a single line arranged to prevent the bucket from twisting and connected at one end with a storage drum and 25 at the other end with an active or operating drum, capable of raising and lowering the bucket and of controlling the same in the ordinary dredging operations.

Another object of the invention is to provide 30 a simple and efficient device, capable of positively locking the jaws or sections of the bucket in an open position and effectively preventing the same from accidentally closing while said bucket is being raised 35 or lowered for dredging under water or beyond the sight of the operator, and adapted also to automatically release the sections when the bucket rests upon the bottom or the material to be dredged.

40 It is also an object of the invention to provide a locking device of this character capable of being controlled automatically by the line without interfering with the free run of the same when the bucket is in its 45 open position.

Furthermore, the invention has for its object to provide a single line dredging bucket 50 equipped with automatic line control devices for locking the bucket in its open position and for holding the bucket closed, and to enable the bucket to be raised and lowered when either open or closed without

affecting the operation of either of the said devices.

Another object of the invention is to arrange the sheaves or pulleys of the bucket so as to secure an additional purchase for digging and closing the bucket without adding outside pulleys or sheaves.

A further object of the invention is to 60 provide a construction adapted to maintain the various parts of the bucket in correct alinement and capable of affording maximum closing power and of applying the same to the jaws or sections at a point 65 where the resistance to the digging or dredging is the heaviest.

With these and other objects in view the invention consists in the construction and novel combination of parts hereinafter fully 70 described, illustrated in the accompanying drawings, and pointed out in the claims appended hereto, it being understood that various changes in the form, proportion, size and minor details of construction, within 75 the scope of the claims, may be resorted to without departing from the spirit or sacrificing any of the advantages of the invention.

In the drawings:—Figure 1 is a side elevation, partly in section, of a dredging bucket constructed in accordance with this invention, the jaws or sections being shown in an open position. Fig. 2 is a vertical sectional view, partly in elevation, illustrating 85 the arrangement of the parts when the jaws or sections are released through contact with the material to be dredged. Fig. 3 is a side elevation of the dredging bucket, the jaws or sections being closed. Fig. 4 is a similar 90 view, taken at right angles to Fig. 3, one of the jaws or sections being partly broken away. Fig. 5 is a horizontal sectional view on the line 5—5 of Fig. 3. Fig. 6 is a detail sectional view taken substantially on the 95 line 6—6 of Fig. 3. Fig. 7 is a horizontal sectional view taken substantially on the line 7—7 of Fig. 3. Fig. 8 is a partial plan view of the bucket. Figs. 9 and 10 are detail views illustrating another form of locking 100 device for holding the jaws or sections in their open position. Figs. 11 and 12 are detail elevations illustrating a form of the invention in which geared pulleys are pro-

vided for the side or run of the line, which is connected with the storage drum. Fig. 13 is a perspective view of the operating lever and the upper and lower pulleys, illustrating the arrangement of the line or cable.

Like numerals of reference designate corresponding parts in all the figures of the drawings.

The accompanying drawings illustrate the 10 preferred embodiment of the invention, while the claims define the actual scope thereof.

Referring to the drawings, the clam shell or orange peel bucket comprises jaws or sections 1, preferably four in number, as clearly 15 illustrated in Fig. 5 of the drawings, but the number of the jaws or sections may, of course, be varied. These jaws or sections, which are constructed of any suitable metal, 20 are provided at their upper edges with inwardly extending radially arranged approximately U-shaped arms 2, consisting of spaced sides and connecting outer portions which are riveted or otherwise secured to 25 the inner faces of the jaws or sections. The inner terminals of the sides are spaced apart to receive lugs 3 of a collar 4, and they are pivoted to the said lugs by bolts 5 or other suitable fastening devices. Instead of providing the radially arranged arms 2 in the 30 form of U-shaped members, they may be constructed in any other desired manner. The jaws or sections are approximately quadrant shaped in plan view, and their side 35 edges are arranged to meet and form a closed receptacle, but in the operation of the dredging device, the sections may be either completely closed or partly closed by means hereinafter fully explained. The collar 4 40 is suitably secured on the lower end of a lower tubular member or sleeve 6, receiving an upper relatively slidable member 7 which is connected with the jaws or sections 1 of the bucket by links 8. The upper member 7 45 consists of a rod or stem and the upper and lower members are slidable on each other in the opening and closing movements of the jaws or sections and are shown as located in the longitudinal center line of the bucket.

The upper slidable member 7 carries at 50 its upper end a head 9, preferably consisting of a disk or plate having a central opening 10 to receive the upper end of the member 7 and provided with projecting peripheral 55 lugs or ears 11 arranged in pairs and receiving the upper ends of the links 8, which are pivoted to the said lugs or ears by bolts 12 or other suitable fastening devices. The links, which are arranged at an inclination, 60 extend downwardly from the head 9 to the jaws or sections 1 of the bucket, and they have angularly bent lower terminal portions 13 arranged exteriorly of the jaws or sections 1 and extending a considerable distance 65 below the upper edges thereof and

pivottally connected with the same by bolts 14 or other suitable fastening devices. The bolts 14 pass through the lower ends of the links 8 and through spaced projecting lugs or ears 15, formed integral with reinforcing plates 16 riveted or otherwise secured to the exterior of the jaws or sections. By pivottally connecting the lower ends of the inclined longitudinally disposed links to the exterior of the jaws or sections below the upper edges thereof, a maximum closing power is obtained and the pressure is applied at the point where the jaws or sections meet with the greatest resistance to their closing or dredging movement.

The jaws or sections are adapted to open to the position illustrated in Fig. 1 of the drawing, and they are locked and maintained in this position while the bucket is being lowered to the bottom or material to 85 be dredged. When the jaws or sections are open, the relatively movable upper member 7 is at the limit of its upward movement and the lower tubular member or sleeve is at the limit of its downward or outward 90 movement. The lower and upper members are held against relative movement when in this position by means of a locking device comprising a lever 17 pivoted at an intermediate point at 18 between spaced projecting 95 ears 19 of the lower member or sleeve 6 at a point between the ends thereof, and its upwardly extending arm is provided with a terminal projecting engaging portion 20 operating in an opening 21 in the tubular member or sleeve 6 and adapted to move inwardly and outwardly into and out of engagement with the lower end 22 of the upper member 7. The lower end 23 of the locking lever 17 is engaged by an anti-friction roller 24 of a latch member 25, pivoted at its inner end at 26 between a pair of spaced ears of the lower tubular member or sleeve and composed of spaced sides and an outer connecting portion.

The antifriction roller 24 is mounted at the inner portion of the latch lever 25, and the lower end 23 of the locking lever 17 extends between the sides of the latch lever beyond the antifriction roller and is provided at its lower end with a laterally projecting pin 27, forming stops for limiting the downward swinging of the latch lever. The locking lever 17 is provided at its lower end 23 with an intermediate outward bend 28, adapted to permit the lower end of the locking lever 17 to swing inwardly when the latch lever 25 is raised, as illustrated in Fig. 2 of the drawings. When the locking lever 17 is in engagement with the upper member 7, the latch lever 25 is in a horizontal position, and engages and holds the lower end 23 of the locking lever 17 against inward movement. The latch lever 25 is tripped by means of an approximately ver-

tical rod or member 29, carried by a transverse operating lever 30 mounted on the lower portion of the sleeve or tubular member 6 above the collar 4. The lever 30 is provided at an intermediate point with an enlargement 31 having an opening 32 for the reception of the tubular member or sleeve 6, and it is pivoted to the same by a horizontal bolt 33 or other suitable fastening device. One arm 34 of the operating lever is shorter and lighter than the other arm 35, and the shorter arm is provided with a slot 36 in which is pivoted a lug or ear 37 of a bearing bracket 38. A pin 39 passes through the arm 34 and the lug or ear 37 of the bearing bracket, in which is mounted a grooved pulley or sheave 40. The trip rod or arm 30 which lifts the latch lever 25 consists of a vertical rod or member 29 preferably secured to the bearing bracket 38 at the outer side thereof and projecting above the same and the grooved pulley or sheave 40. The longer arm 35 of the operating lever is provided with a slot or opening 41, in which is mounted a grooved pulley or sheave 42. The arm 35 is provided with an approximately U-shaped guard 43, consisting of spaced sides secured to the exterior of the arm 35 at opposite sides of the slot 41 and an outer connecting portion located beyond the arm and arranged in spaced relation with the outer edge of the pulley or sheave 42. When the line or cable 44 to which the dredging bucket is connected slackens by reason of the open bucket coming in contact with the material to be dug or excavated, the heavier arm 35 of the operating lever 30 swings the lighter arm 34 upwardly and carries the tripping device 29 upwardly into contact with the latch lever 25 and lifts the same sufficiently to release the locking lever 17, and the relatively slidable member 7 moves downwardly a sufficient distance to carry the lower end 22 of the said upper member 7 beyond the engaging portion of the locking lever 17. There is sufficient slack or looseness in the fastening devices of the side bars or links 8 to permit this movement of the upper member, which always has a tendency, due to its weight, to slide downwardly into the lower tubular member 7 or sleeve 6. The gravity acting operating lever 30, which is normally maintained by the line with its heavier arm 35 lifted, is limited in such movement by a lug or projection 43^a extending upwardly from the heavier arm at the inner end thereof and arranged to engage the lower tubular member or sleeve 6. Any other suitable means, however, may be employed for limiting the movement of the gravity acting operating lever.

Various forms of locking devices may be employed for holding the upper and lower members against relative movement to lock

the jaws or sections of the bucket in their open position, and in Figs. 9 and 10 is illustrated another form of the invention, in which a locking lever 45 is maintained in engagement with the relatively slidable upper member 7 by means of a toggle connection 46 between its lower end and the lower sleeve or member 6. The toggle 46 is composed of inner and outer links 47 and 48, pivoted together at their adjacent ends at 49 and similarly connected at their other ends at 50 and 51 to the lower sleeve or member 6 at the lower end of the locking lever 45. The link 48 is provided at its inner pivoted end with a lug or projecting portion 52, extending over and adapted to rest upon the upper edge of the inner link 47 to limit the downward movement of the links, which are adapted to break upwardly to permit the lower arm of the operating lever to swing inwardly, as shown in Fig. 10 of the drawings.

The line or cable 44 is connected at its ends to an active or operating drum (not shown), and to a storage drum (not shown). The run or stretch 53 of the line extends downwardly to the guide pulley or sheave 42 at one end of the operating lever 30, passing behind an upper side guide pulley or sheave 54. The line 53 then extends upwardly and passes over a central grooved guide pulley or sheave 55 and then downwardly to the pulley or sheave 40 at the other end of the operating lever 30. From the lower guide pulley 40 the line extends upwardly to and makes two complete turns around a ratchet pulley or sheave 56, having a ratchet element 57 adapted to be engaged by a pawl or dog 58 for holding the ratchet pulley or sheave 56 against rotary movement in one direction, while the closed bucket is being raised with its load. The other run or stretch 59 of the line extends from the ratchet pulley 56 to the storage drum. The bucket is therefore carried by a loop of the line, of which loop the runs 53 and 59 constitute a part. The pulleys or sheaves 40 and 42 bear the entire weight of the bucket when the latter is closed, and is being raised with its load, and the said pulleys or sheaves 40 and 42 also bear the weight of the bucket when the latter is open for loading. When the bucket is in the act of opening, the weight is borne mostly by the upper sheave 55, and when the jaws or sections are in the act of closing upon the substance or material being dredged or operated on by the bucket, the weight of the latter is on the pulleys or sheaves 40 and 42. The upper side guide sheave 54 is mounted in a bearing bracket or arm 60 secured to the head 9 at one edge thereof and projecting therefrom, as clearly illustrated in Fig. 7 of the drawings. The central pulley or sheave 55 and the ratchet sheave 56 are mounted on a horizontal shaft

or axle, preferably in the form of a bolt 61, and extending through the hubs of the pulleys 55 and 56 and through bearing arms 62, extending upwardly from the head 9 at opposite sides thereof. These bearing arms 62 may be formed integral with the head or be fixed thereto in any other desired manner.

The ratchet element 57 consists of a toothed rim or flange mounted on the outer side of the pulley 56, but it may be constructed in any other desired manner. The pawl or dog 58, which is approximately T-shaped, is mounted between a pair of upwardly projecting lugs or ears 63 on a suitable pivot 64, and it has an upwardly extending arm or portion arranged to engage the ratchet member, an outer arm or portion 65, and an inner arm 66 extending over the head and provided with a depending approximately L-shaped portion 67. The depending portion 67 extends beneath the head 9 and constitutes a stop for limiting the upward movement of the inner arm 66 and the outward movement of the engaging arm. The outer arm or portion 65 is provided with a slot or opening 68, through which passes the upper end of an operating rod 69, having its lower portion guided in vertically aligned openings of upper and lower lugs 70 and 71, and carrying stops 72 and 73, adjustably mounted on the lower portion of the operating rod 69 and adapted to engage with the upper and lower guide lugs 70 and 71. The upper portion 74 of the operating rod 69 is threaded for the reception of a pair of nuts 75, constituting an adjustable stop arranged to engage and rest upon the outer portion or arm 65 of the pawl or dog 58 for holding the latter out of engagement with the teeth 57 of the ratchet sheave or pulley 56. The lower adjustable stops 72 and 73 are preferably in the form of set collars and are adapted to be secured at different points on the lower portion of the operating rod 69, which is provided with an intermediate angularly bent portion 76 for offsetting its lower portion inwardly from the plane of the upper portion.

The operating rod 69 is adapted to maintain the pawl or dog 58 out of engagement with the ratchet pulley 56 to permit the latter to rotate freely in either direction while the jaws or sections of the bucket are locked in their open position, as illustrated in Fig. 1 of the drawings, whereby the bucket may be raised and lowered freely by drawing in or paying out the line 53. When, by paying out the line 53, the bucket is lowered sufficiently to rest upon the material to be dredged, excavated, or otherwise handled, the line 53 becomes somewhat slackened and then the relatively long arm 35, which is heavier than the relatively short arm 34 of the lever 30, swings downwardly from the slightly upwardly inclined position illus-

trated in Fig. 1 to the slightly downwardly inclined position illustrated in Fig. 2. This correspondingly elevates the relatively short lighter arm of the lever 30 and carries the tripping device 29 into contact with the latch or holding lever 25, lifting the latter and thereby releasing the locking lever 17. The engaging portion 20 of the locking lever 17 is beveled at the upper edge, whereby the locking lever 17 will be positively moved outwardly out of engagement with the said upper member 7 by the downward movement of the same, which, as previously explained, has sufficient play or movement to carry its lower end 22 from the position illustrated in Fig. 2. In this manner, through the action of the line 44, the locking device 17 for holding the jaws or sections is positively and automatically tripped and the said jaws or sections released and permitted to close. The line 53 is now drawn taut, which slides the upper section 7 downwardly into the lower tubular section 6 from the position illustrated in Fig. 2 of the drawings to that shown in Fig. 3, thereby closing the jaws or sections of the bucket. While in this position the bucket, with its load, is raised and carried to the position for dumping. When, through the downward movement of the upper section 7, the lower stop 73 of the operating rod 69 comes in contact with the lower guide 71, the latter will support the operating rod 69 so that the further downward movement of the upper section 7 will carry the outwardly extending arm 65 of the pawl or dog downwardly beyond and out of engagement with the stop formed by the nuts 75. This will release the pawl or dog 58 and permit the heavier arm 66 thereof to swing the engaging portion of the same into engagement with the ratchet element of the sheave 56.

When the pawl or dog 58 is in engagement with the ratchet element 57 of the sheave 56, the sheave is locked against rotation in one direction. However, when the line 59 is held against movement, and the line 53 is being drawn in for the purpose of raising the bucket, the sheave 56 will be caused to rotate in the direction of the arrow and wind upon the line 59. If the line 53 should become slack the pawl 58 would prevent the sheave from rotating in an opposite direction, that is in a direction contrary to that indicated by the arrow. If it is desired to lower the bucket without dumping the load, the line 53 will be held, and upon the paying out of the line 59 the sheave 56 will continue to rotate in the direction indicated by the arrow in Fig. 3 until line 59 is held against further movement. Assuming that the buckets have now been lowered, for the purpose of dumping the buckets the line 59 will be held and the line 53 slackened by paying out the line, the paying out of the line will

cause the movable member 6 to slide or move downwardly upon the member 7, and this movement will force the jaws or sections 1 of the bucket apart causing the 5 contents of the bucket to be discharged. The pawl or dog 58 prevents the sheave 56 from rotating in the direction opposite to that indicated by the arrow. The bucket is thereby held suspended on the line 59 by 10 the two complete turns around the sheave 56, which is stationary through its engagement with the ratchet pawl or dog 58.

On a continued paying out and slackening of the line 58, the lower tubular section 15 or sleeve 6 is permitted to slide downwardly on the upper section 7 until the locking lever 17 reengages the lower end 22 of the said upper section 7 and the latch or holding lever 25 drops into engagement with the 20 lower end of the locking lever 17 for retaining the engaging portion 20 therof in its engaging position beneath the lower end of the said upper section or member 7. In this manner the jaws or sections of the bucket 25 are opened for dumping or loading and are locked in the open position shown in Fig. 1. When, through the downward movement of the lower tubular member or sleeve 6, the lower guide lug 71 is carried downwardly, 30 the operating rod 69 is lowered until its upper stop, formed by the nuts 75, engages and rests upon the outwardly projecting arm or portion of the pawl or dog. In the said downward movement of the tubular member or sleeve 6, the upper guide 70 is carried into engagement with the adjustable stop 72 and positively disengages the dog 58 from the ratchet element of the sheave 56. The weight of the rod 69 is sufficient to hold the dog 59 in the disengaged position even when the lug 70 moves away from the stop 72, and therefore maintains the pawl or dog out of engagement with the ratchet element of the sheave 56 while the 45 jaws or sections are in their open position. By locking the jaws or sections of the bucket open and positively retaining the pawl or dog 58 out of engagement with the ratchet element 56, the line is permitted to run freely through the bucket and the latter may be raised or lowered in its open condition, and there is no liability of the jaws or sections accidentally closing before the bucket rests upon the material to be 50 dredged, excavated, or handled. The stops 75, 72, 73 at the upper and lower portions of the operating rod are adapted to be adjusted for causing the pawl or dog 58 to engage with the ratchet wheel 57 either when the jaws or sections of the bucket are 55 entirely closed or partially closed, so that the bucket and its load may be elevated with the jaws or sections in the desired position.

The pulleys or sheaves may be varied in size to adapt the bucket to the class of ma-

terial to be operated on, and should it be desired to increase the frictional contact between the line 58 and the ratchet pulley or sheave 56 when the pawl or dog 58 is in engagement with the latter, a pair of pulleys or sheaves 77 and 78, arranged one above the other, may be employed, as illustrated in Figs. 11 and 12 of the drawings. These pulleys or sheaves 77 and 78 are connected with gearing consisting of gear 75 wheels 79 and 80 and an intermediate pinion 81 meshing with the gear wheels and adapted to cause the upper and lower pulleys or sheaves 77 and 78 to rotate in the same direction. The upper and lower pulleys or sheaves 77 and 78 are grooved to receive the line, and the latter is designed to make one complete turn around each of these pulleys or sheaves. The lower pulley or sheave 78 is provided with a ratchet element 82 and operates in a similar manner to the ratchet sheave 56.

The device for locking and the means for holding the pawl of the ratchet mechanism out of engagement with the ratchet element 90 does not affect the free run of the line 44 through the bucket or produce any wear on the said line, and by connecting one end of the line with a storage drum and the other end with an active or operating drum, the 95 outer or operating portion of the line receives all of the wear and may be readily removed when desired, and a new or unused portion of the line may be run off the storage drum. In this manner it is only necessary to discard the worn portion of the line. By connecting the ends of the line with the operating and storage drums, and causing the lines 53 and 59 to be drawn taut, the line is looped and a double purchase for 100 closing the bucket and for hoisting the same is secured, without the use of outside pulleys or sheaves. Also, the runs or stretches of the line are spaced apart to prevent the 105 line from twisting.

110 What is claimed is:—

1. A bucket of the class described, including pivotally mounted jaws or sections arranged to swing outwardly and inwardly to open and close the bucket, direction-changing and bucket-operating sheaves on the bucket, a line looped through the direction-changing and bucket-operating sheaves and movable in either direction therethrough, means for temporarily preventing 115 the line from moving in one direction through the bucket, and automatically operable means for locking the jaws or sections in their open position without affecting the free run of the line.

2. A bucket of the class described, including pivotally mounted jaws or sections arranged to swing outwardly and inwardly to open and close the bucket, direction-changing and bucket-operating sheaves on 120

125

130

the bucket, a line looped through the direction-changing and bucket-operating sheaves and movable in either direction therethrough, means for temporarily preventing the line from moving in one direction through the bucket, and automatically operable means for locking the jaws or sections in their open position without affecting the free run of the line, and the bucket 10 also being provided with means under the control of the line for moving the automatically operable means from locking position.

3. A bucket of the class described, including pivotally mounted jaws or sections arranged to swing outwardly and inwardly to open and close the bucket, means for connecting the bucket with a line, locking means for positively holding the jaws or sections in their open position, means for releasing the locking means located in the bucket to be at all times wholly above the bottom thereof, and means on the lock releasing means engaged by and under the control of the line for causing the active operation 25 of the lock releasing means on slackening of the line.

4. A bucket of the class described, including pivotally mounted jaws or sections arranged to swing outwardly and inwardly to open and close the bucket, means for connecting the bucket with a line, a device for locking the jaws or sections in their open position, and a tripping device for the locking device separate therefrom and engaged 30 by and under the control of the line for active operation on slackening of the line, said tripping device being located in the bucket to be at all times wholly above the bottom thereof.

40 5. A bucket of the class described, including pivotally mounted jaws or sections arranged to swing outwardly and inwardly to open and close the bucket, means for connecting the bucket with a line, means for positively locking the jaws or sections in their open position, and releasing means for the locking means separate from said locking means and located in the bucket to be at all times wholly above the bottom thereof 45 and engaged by and under the control of the line, whereby the releasing means is rendered active on the slackening of the line caused by the engagement of the bucket with the material to be dredged.

55 6. A bucket of the class described, including jaws or sections, means for suspending the bucket from a single line looped through the bucket and for permitting the line to move through the bucket for raising and 60 lowering the latter, means for locking the jaws or sections in their open position without affecting the free run of the line through the bucket, and releasing means for the locking means separate from and independent thereof and located to be at all times

wholly above the bottom of the bucket, said releasing means having means engaged by the line for the control of the releasing means, whereby the slackening of the line due to the engagement of the bucket with the material to be dredged causes the active operation of the releasing means.

7. A bucket of the class described, including jaws or sections, means for suspending the bucket from a line and for permitting the line to run through the bucket for raising and lowering the latter, a locking device for the jaws or sections for holding them in the open position without affecting the free run of the line through the bucket, 75 and a tripping device for the locking device located in the bucket to be at all times wholly above the bottom thereof, said tripping device having means engaged by the line to hold the latter in the inactive position while the line is taut and for causing the active operation of the tripping device by slackening of the line due to the engagement of the jaws of the bucket with the material to be dredged. 90

8. A bucket of the class described, including jaw or sections, means for suspending the bucket from a line and permitting the latter to run through the bucket for raising and lowering said bucket, a locking device for holding the jaws in the open position without affecting the free run of the line through the bucket, and a gravity acting tripping device separate from and independent of the locking device and located 95 in the bucket to be at all times wholly above the bottom thereof, said tripping device having means engaged by and under the control of the line to normally maintain said tripping device in the inoperative position and to release the tripping device to the action of gravity on the slackening of the line due to the engagement of the bucket with the material to be dredged. 105

9. A bucket of the class described, comprising jaws or sections, means for suspending the bucket from a line and for permitting the line to run through the bucket for raising and lowering the latter, locking means for holding the jaws or sections in their open position including a pivoted lever and a device for holding the lever in its engaged position, and a tripping device for the locking means having means engaged by the line for holding the tripping device in 110 the inactive position and movable on the slackening of the line caused by the engagement of the bucket jaws with the material to be dredged to release the pivoted lever to move the locking means to the unlocked position. 120

10. A bucket of the class described comprising jaws or sections, means for suspending the bucket from a line and for permitting the line to run through the bucket for 130

raising and lowering the same, means for locking the jaws or sections in their open position, a pivotally mounted device for holding the locking means in its engaging position, a gravity acting lever normally maintained in an inoperative position by the line, and a tripping device carried by the gravity acting lever for moving the pivotally mounted device out of engagement with the locking means.

11. A bucket of the class described comprising jaws or sections, means for suspending the bucket from a line and for permitting the line to run through the bucket for raising and lowering the same, means for locking the jaws or sections in their open position, a pivoted latch lever arranged to hold the locking means in its engaging position, a gravity acting lever arranged below the latch lever and normally maintained in an inoperative position by the line, and a tripping device carried by the gravity acting lever and arranged to lift the latch lever out of engagement with the locking means when the line is slackened.

12. A bucket of the class described including upper and lower relatively slidable members, pivotally mounted jaws or sections connected with said members and opened and closed by said members in their relatively slidable movements, means for connecting the bucket with a line, a locking device mounted on one of said members and arranged to engage the other member for holding the jaws or sections in their open position, and release means for the locking device separate from and independent of said locking device and provided with means engaged by the line for the control of the release means with the latter located in the bucket to be at all times above the bottom of the bucket, and said release means being movable by the slackening of the line due to the engagement of the bucket with the material to be dredged to cause the locking device to move to the unlocked position.

13. A bucket of the class described including upper and lower relatively slidable members, pivotally mounted jaws or sections connected with the said members and opened and closed by the relative slidable movement of the same, means for connecting the bucket with a line, a locking lever pivotally mounted on one of the said members and arranged to engage the other member for holding the jaws or sections in their open position, a movable latch for retaining the said lever in its engaging position, and an operable tripping device normally maintained out of engagement with the latch by the line and automatically movable into engagement with the latch when the line is slackened, whereby the locking lever is unlatched.

14. A bucket of the class described including upper and lower relatively slidable members, pivotally mounted jaws or sections connected with the said members and opened and closed by the relative slid- 70 able movement of the same, means for connecting the bucket with a line, a locking device mounted on one of the said members, the other member being provided with a portion for engaging with the said device 75 and said members automatically movable by gravity to a position beyond and out of engagement with the said locking device when free to move, a latch for retaining the locking device in its engaging position, and 80 means operable by the line for releasing the locking device.

15. A bucket of the class described includ- 85 ing upper and lower relatively slidable members, pivotally mounted jaws or sec- tions connected with the said members and opened and closed by the relative slidable movement of the same, means for connecting the bucket with a line, a locking lever pivotally mounted on the lower member and arranged to engage the upper member, a latch carried by the lower member for retaining the locking lever in its engaging position, a gravity acting lever mounted on the lower member and normally held in an in- 90 operative position by the line, and a tripping device carried by the gravity acting lever and movable into engagement with the latch for releasing the locking lever when the line is slackened. 95

16. A bucket of the class described includ- 100 ing upper and lower relatively slidable members, pivotally mounted jaws or sec- tions connected with the said members and opened and closed by the relative slidable movement of the same, means for connecting the bucket with a line, a locking lever pivotally mounted on the lower member and having its upper arm arranged to engage the upper member to hold the jaws or sec- tions in an open position, said lever hav- 105 ing a lower arm provided at an intermedi- ate point with an outward bend, a latch lever pivotally mounted on the lower mem- ber and arranged to engage the lower arm of the locking lever below the said bend, said locking lever being provided with means for supporting the latch lever in such engaging position, a tripping device for moving the latch lever upwardly to the bend of the locking lever, and a gravity acting lever carrying the tripping device and connected with the line for maintaining the tripping device out of engagement with the latch lever. 110

17. A bucket of the class described includ- 115 ing pivotally mounted jaws or sections, means for suspending the bucket from a line and for permitting the line to run through the bucket for raising and lower- 120 125 130

ing the same, means automatically operated in the closing movement of the jaws or sections for checking the movement of the line in one direction without interfering with the 5 free movement of the line in the opposite direction, whereby when one end of the line is drawn in the bucket will be elevated, and when paid out, the bucket will be checked and the line slackened, and means operable 10 by such slackening of the line for opening the jaws or sections to dump the bucket.

18. A bucket of the class described comprising relatively movable members, pivotally mounted jaws or sections connected 15 with the said members and opened and closed by the relative movement thereof, means for connecting the said members with a line for suspending the bucket and for permitting the line to run freely for 20 raising and lowering the bucket, said line being adapted to close the jaws or sections when the members are free to move, and means operable through the closing movement of the jaws or sections for checking 25 the movement of the line in one direction without interfering with its free movement in the opposite direction.

19. A bucket of the class described comprising relatively movable members, pivotally mounted jaws or sections connected 30 with the said members and opened and closed by the relative movement thereof, means for connecting the said members with a line for suspending the bucket and for 35 permitting the line to run freely for raising and lowering the bucket, said line being adapted to close the jaws or sections when the members are free to move, a pawl and ratchet device for checking the movement 40 of the line in one direction without interfering with its free movement in the opposite direction, and means connected with the said members for throwing the pawl into and out of its engaging position when 45 the jaws or sections are closed and opened.

20. A bucket of the class described comprising relatively movable members, pivotally mounted jaws or sections connected with the said members and opened and 50 closed by the relative movement thereof, means for connecting the said members with a line for suspending the bucket and for permitting the line to run freely for raising and lowering the bucket, said line being 55 adapted to close the jaws or sections when the members are free to move, a pawl and ratchet device for checking the movement of the line in one direction without interfering with its free movement in the opposite direction, and means connected with the said members for throwing the pawl into and out of its engaging position when 60 the jaws or sections are closed and opened, the latter means being adjustable to vary 65 the closing movement of the jaws or sections.

21. A bucket of the class described comprising relatively movable members, pivotally mounted jaws or sections connected with the said members and opened and closed by the relative movement thereof, 70 means for connecting the said members with a line for suspending the bucket and for permitting the line to run freely for raising and lowering the bucket, said line being adapted to close the jaws or sections when 75 the members are free to move, a pawl and ratchet device carried by one of the said members for checking the movement of the line in one direction without interfering with the free movement of the line in the 80 opposite direction, and operating means for connecting the pawl with the other member to throw the pawl into and out of engagement with the ratchet.

22. A bucket of the class described comprising relatively movable members, pivotally mounted jaws or sections connected with the said members and opened and closed by the relative movement thereof, 85 means for connecting the said members with a line for suspending the bucket and for permitting the line to run freely for raising and lowering the bucket, said line being adapted to close the jaws or sections when 90 the members are free to move, a pawl and ratchet device carried by one of the said members for checking the movement of the line in one direction without interfering with the free movement of the line in the opposite direction, an operating rod 95 or member slidably connected with the pawl and adapted to hold the same out of engagement, and means mounted on the other member and coacting with the rod or member for permitting the pawl to engage the 100 ratchet.

23. A bucket of the class described comprising relatively movable members, pivotally mounted jaws or sections connected with the said members and opened and 110 closed by the relative movement thereof, means for connecting the said members with a line for suspending the bucket and for permitting the line to run freely for raising and lowering the bucket, said line 115 being adapted to close the jaws or sections when the members are free to move, a pawl and ratchet device carried by one of the members and comprising a rotary ratchet element, and a pawl automatically movable 120 into engagement with the ratchet element, said pawl and ratchet device being adapted to check the movement of the line in one direction without interfering with the free movement of the same in the opposite direction, and operating means connected 125 with the pawl and with the other member for throwing the pawl out of engagement when the jaws or sections are opened and for permitting the pawl to engage the 130

ratchet element when the jaws or sections are closed.

24. A bucket of the class described comprising relatively movable members, pivotally mounted jaws or sections connected with the said members and opened and closed by the relative movement thereof, means for connecting the said members with a line for suspending the bucket and for 5 permitting the line to run freely for raising and lowering the bucket, said line being adapted to close the jaws or sections when the members are free to move, a pawl and ratchet device carried by one of the members 70 and comprising a rotary ratchet element, and a pawl automatically movable into engagement with the ratchet element, said pawl and ratchet device being adapted to check the movement of the line in one direction without interfering with the free movement of the same in the opposite direction, an operating rod connected with the pawl and adapted to hold the same out of engagement, spaced guiding means mounted 75 on the other member and receiving the operating rod, and adjustable stops mounted on the rod between the guiding means and arranged to be engaged by the same to release the pawl in one movement of the members 80 and to hold the pawl positively out of engagement in the other movement of the members.
25. A bucket of the class described comprising relatively movable members, pivotally mounted jaws or sections connected with the said members and opened and closed by the relative movement thereof, means for connecting the said members with a line for suspending the bucket and for 85 permitting the line to run freely for raising and lowering the bucket, said line being adapted to close the jaws or sections when the members are free to move, a pawl and ratchet device carried by one of the members 90 and comprising a rotary ratchet element, and a pawl automatically movable into engagement with the ratchet element, said pawl and ratchet device being adapted to check the movement of the line in one direction without interfering with the free movement of the same in the opposite direction, an operating rod connected with the pawl and adapted to hold the same out of engagement, spaced guiding means mounted 95 on the other member and receiving the operating rod, and a stop mounted on the rod between the guiding means and arranged to permit the rod to be lifted by the guiding means for releasing the pawl.
26. A bucket of the class described comprising relatively movable members, pivotally mounted jaws or sections connected with the said members and opened and closed by the relative movement thereof, means for connecting the said members with a line for suspending the bucket and for 100 permitting the line to run freely for raising and lowering the bucket, means for locking the members against movement for holding the bucket open without affecting the movement of the line, and means automatically operated by the line for releasing the members to permit the bucket to close.
27. A bucket of the class described comprising relatively movable members, pivotally mounted jaws or sections connected with the said members and opened and closed by the relative movement thereof, means for connecting the said members with a line for suspending the bucket and for 105 permitting the line to run freely for raising and lowering the bucket, means for locking the members against movement for holding the bucket open without affecting the movement of the line, and means automatically operated by the line for releasing the members to permit the bucket to close.
28. A bucket of the class described comprising relatively movable members, pivotally mounted jaws or sections connected with the said members and opened and closed by the relative movement thereof, means for connecting the said members with a line for suspending the bucket and for 110 permitting the line to run freely for raising and lowering the bucket, means for locking the members against movement for holding the bucket open without affecting the movement of the line, means automatically operated by the line for releasing the members to permit the bucket to close, and means for checking the movement of the line in one direction without interfering with the free movement thereof in the opposite direction, said means being thrown into and 115 out of action by the movements of the members in opening and closing the bucket.
29. A bucket of the class described including upper and lower relatively slidable members, pivotally mounted jaws or sections connected with the members and opened and closed by the relative movement thereof, sheaves carried by the members and adapted to receive a line, a pawl and ratchet device connected with one of the sheaves for check- 120
30. A bucket of the class described comprising relatively movable members, pivotally mounted jaws or sections connected with the said members and opened and closed by the relative movement thereof, means for connecting the said members with a line for suspending the bucket and for 125 permitting the line to run freely for raising and lowering the bucket, said line being adapted to close the jaws or sections when the members are free to move, a pawl and ratchet device carried by one of the members and comprising a rotary ratchet element, and a pawl automatically movable into engagement with the ratchet element, said pawl and ratchet device being adapted to check the movement of the line in one direction without interfering with the free movement of the same in the opposite direction, an operating rod connected with the pawl and adapted to hold the same out of engagement, spaced guiding means mounted on the other member and receiving the operating rod, and adjustable stops mounted on the rod between the guiding means and arranged to be engaged by the same to release the pawl in one movement of the members and to hold the pawl positively out of engagement in the other movement of the members.
31. A bucket of the class described comprising relatively movable members, pivotally mounted jaws or sections connected with the said members and opened and closed by the relative movement thereof, means for connecting the said members with a line for suspending the bucket and for 130 permitting the line to run freely for raising and lowering the bucket, said line being adapted to close the jaws or sections when the members are free to move, a pawl and ratchet device carried by one of the members and comprising a rotary ratchet element, and a pawl automatically movable into engagement with the ratchet element, said pawl and ratchet device being adapted to check the movement of the line in one direction without interfering with the free movement of the same in the opposite direction, an operating rod connected with the pawl and adapted to hold the same out of engagement, spaced guiding means mounted on the other member and receiving the operating rod, and adjustable stops mounted on the rod between the guiding means and arranged to be engaged by the same to release the pawl in one movement of the members and to hold the pawl positively out of engagement in the other movement of the members.

ing the movement of the line in one direction without interfering with its movement in the other direction, means for carrying the pawl out of engagement in the opening movement of the jaws or sections and for moving the pawl into engagement in the closing movement of the said jaws or sections, and means for locking the members against movement to hold the jaws or sections in their open position.

30. A bucket of the class described including upper and lower relatively slidable members, pivotally mounted jaws or sections connected with the members and opened and closed by the relative movement thereof, sheaves carried by the members and adapted to receive a line, a pawl and ratchet device connected with one of the sheaves for checking the movement of the line in one direction without interfering with its movement in the other direction, means for carrying the pawl out of engagement in the opening movement of the jaws or sections and for moving the pawl into engagement in the closing movement of the said jaws or sections, a locking device for holding the members against movement to retain the jaws or sections in their open position, and means operable by the line for releasing the said members to permit the jaws or sections to close.

31. A bucket of the class described including upper and lower relatively movable members, pivotally mounted jaws or sections connected with the members and opened and closed by the relative movement of the same, a gravity operating lever pivotally mounted at an intermediate point on the lower member, one of the arms of the lever being heavier than the other, sheaves mounted on the arms of the lever, other sheaves carried by the upper member, a line arranged on the said sheaves and adapted to be run through the bucket to raise and lower the same, a ratchet element connected with one of the sheaves, a pawl movable into and out of engagement with the ratchet element in the closing and opening movements of the jaws or sections, a locking device mounted on the lower member and arranged to engage the upper member for holding the jaws or sections in their open position, a latch for holding the locking lever in its engaging position, and a tripping device carried by the operating lever and arranged to unlatch the locking lever.

32. A bucket of the class described including upper and lower relatively slidable members, pivotally mounted jaws or sections connected with the members and opened and closed by the relative movement of the same, a head carried by the upper member, centrally arranged upper sheaves mounted on the head, one of the sheaves being provided with a ratchet ele-

ment, a gravity acting lever pivotally mounted intermediate of its ends on the lower member and provided at its arms with sheaves, a side guide sheave also carried by the said head, a line arranged on the sheaves, a pawl mounted on the head and connected with and operated by the lower member for engaging it with and disengaging it from the ratchet element, and locking mechanism for holding the members against relative movement to maintain the jaws or sections in their open position, and means carried by the gravity acting lever for releasing the members to permit the jaws or sections to close.

33. A dredging bucket comprising pivotally mounted jaws or sections arranged to swing outwardly and inwardly for opening and closing the bucket, a suspension line for and looped through the bucket, direction-changing and holding means on the bucket for the line, whereby with one run of the line held against movement, the other run of the line may be paid out and drawn in for lowering and raising the bucket throughout the full extent of up and down travel of said bucket, and means for causing the jaws of the bucket to be swung to the open position on slackening the second named run of the line.

34. A bucket of the class described including members having relative inward and outward movement, jaws or sections connected with the said members and opened and closed by the outward and inward movements thereof, pulleys or sheaves carried by the said members, a line arranged on the pulleys or sheaves and supporting the bucket, whereby the weight of the latter will tend to urge the jaws or sections inwardly, means for locking the jaws or sections in their open position, said locking means being automatically operated through the slackening of the line to release the jaws or sections, and means for checking the movement of the line from the said pulleys in one direction, the latter means permitting the free movement of the line in the opposite direction for raising the bucket.

35. A bucket of the class described including members having relative inward and outward movement, jaws or sections connected with the said members and opened and closed by the outward and inward movements thereof, pulleys or sheaves carried by the said members, a line arranged on the pulleys or sheaves and supporting the bucket, whereby the weight of the latter will tend to urge the jaws or sections inwardly, means for locking the jaws or sections in their open position, said locking means being automatically operated through the slackening of the line to release the jaws or sections, and a device for checking the

movement of the line in one direction when the jaws or sections are closed, said device comprising elements arranged to be thrown into and out of action by the inward and outward movements of the members.

36. A bucket of the class described including upper and lower slidable members having relative inward and outward movements, jaws or sections connected with the said members and opened and closed by the outward and inward movements thereof, pulleys or sheaves carried by the said members, a line arranged on the pulleys and supporting the bucket, and means thrown into and out of operation by the inward and outward movements of the said members for checking the movement of the line in one direction when the jaws or sections are closed, whereby the line may be slackened to permit the jaws or sections to open for dumping the contents of the bucket.

37. A bucket of the class described including upper and lower slidable members having relative inward and outward movements, jaws or sections carried by the said members and opened and closed by the outward and inward movements thereof, pulleys or sheaves carried by the said members, a line arranged on the pulleys or sheaves and supporting the bucket, said line having runs or stretches adapted to be connected with an active or operating drum and with a storage drum, and means thrown into and out of operation by the inward or outward movement of the said members for checking the movement of the line in one direction when the jaws or sections are closed, whereby one of the stretches or runs of the line may be slackened to permit the jaws or

sections to open for dumping the contents of the bucket, and the other stretch or run being adapted to be slackened to permit the bucket to be lowered before dumping.

38. A dredging bucket comprising telescoping members, bucket jaws or sections each connected to and opened and closed by said members in their telescoping movements, sheaves carried by said telescoping members, a line looped through the bucket and arranged on the sheaves with certain of the latter supporting the bucket, and automatic devices carried by one of the telescoping members and in part engaged and controlled by the line for locking the jaws or sections in their open position.

39. A bucket, comprising movable members, jaws pivotally connected to the members, and opened and closed by the relative sliding movement of the members, and automatic means mounted on one of the members adapted to engage the other member for holding the jaws in an open position.

40. A bucket, comprising movable jaws, a line for raising and lowering the jaws, and means automatically operated in the closing movement of the jaws for checking the movement of the line in one direction without interfering with the free movement of the line in the opposite direction, whereby when one end of the line is drawn in the bucket will be elevated.

In testimony, that I claim the foregoing as my own, I have hereto affixed my signature in the presence of two witnesses.

GORDON R. ROWAN.
